US0D1099839S

(12) **United States Design Patent** (10) **Patent No.:** **US D1,099,839 S**
(45) **Date of Patent:** **** Oct. 28, 2025**

(54) **BATTERY POST TERMINAL ASSEMBLY**

(71) Applicant: **EMA-US, Inc.**, Huntington Woods, MI (US)

(72) Inventors: **Scott Ritchie**, Huntington Woods, MI (US); **William Olsen**, Birmingham, MI (US); **Jum Pil Kim**, ChoenAn (KR)

(73) Assignee: **EMA-US, Inc.**, Huntington Woods, MI (US)

(**) Term: **15 Years**

(21) Appl. No.: **29/828,704**

(22) Filed: **Feb. 28, 2022**

Related U.S. Application Data

(63) Continuation of application No. 16/485,155, filed as application No. PCT/US2018/017788 on Feb. 12, 2018, now Pat. No. 11,264,740.
